J. F. GRACE.

CONDENSER.

FILED MAR. 20, 1920.

UNITED STATES PATENT OFFICE.

JOHN F. GRACE, OF KEARNY, NEW JERSEY, ASSIGNOR TO WORTHINGTON PUMP AND MACHINERY CORPORATION, A CORPORATION OF VIRGINIA.

CONDENSER.

Application filed March 20, 1920. Serial No. 367,448.

To all whom it may concern:

Be it known that I, JOHN F. GRACE, a citizen of the United States, residing at Kearny, county of Hudson, and State of New Jersey, have invented certain new and useful Improvements in Condensers, fully described and represented in the following specification and the accompanying drawings, forming a part of the same.

10 This invention relates to improvements in jet condensers, and especially to parallel flow condensers, the object of the invention being to provide an improved construction by which a more efficient action shall be secured, and which shall be simple, cheap, and convenient in manufacture and use.

An especial object of the invention is the provision of an improved and efficient device for cooling and reducing the volume 20 of the air having a very large cooling surface in a simple, cheap and compact construction.

For a full understanding of the invention a detailed description of a condenser embodying all the features of the invention in their preferred form will now be given in connection with the accompanying drawing forming a part of this specification, and the features forming the invention then specifically pointed out in the claims.

In the drawings:—

Figure 1 is a vertical central section of the condenser.

Figure 2 is a section on the line 2—2 of Figure 1.

Fig. 3 is a section on line 3—3 of Fig. 2;

Fig. 4 is a section on the line 4—4 of Fig. 2, showing a slightly modified form of the valve shown in Fig. 2;

40 Figure 5 is a section on the line 5—5 of Figure 1.

Referring to the drawing, the condenser shell is preferably made in sections, as shown, A being the hot well section, having the usual tail pump connection 11, B the air cooling section having outlet 12, connected to the usual dry vacuum pump or other exhausting means, and C the condensing section having steam and condensing water inlets 13, 14, respectively. These sections are preferably arranged as shown, so that each lower section supports those above it, and one section may be turned upon the other

to bring the connections 11, 12 and 14 in any desired position without any change of 55 patterns or effect on the other castings, thus enabling the connections to the injection, air and tail pumps to be made in any direction.

Referring now to the interior construction of the condenser, the inlet section C is 60 provided with a conical partition 15, extending into the section B and dividing the section C into a condensing chamber 16 and a condensing water supply chamber 17, connected by passages 18 to a plurality of 65 nozzle chambers 19, preferably four in number, having spray nozzles 20 suitably secured therein.

I preferably provide an annular downwardly projecting cooling chamber 21 which 70 is open at its upper end to the water chamber 17 and extends into the section B and surrounds the lower end of the partition 15 to form the cooling element for the air passing from section B through connection 12. 75 The section B is provided with two annular flanges 22, 24, bearing against section C to form annular passages 25 and 23. A portion of the flange 24 is cut away on the same side of the condenser as connection 12, to 80 form a port 26 connecting passage 25 with the interior of the condenser and flange 22 has port 27 on the opposite side of the condenser connecting the passages 25, 23. The bottom of section B preferably is so formed 85 that it partly covers the hot well section A to prevent eddies from carrying water into the air suction.

The operation is as follows:—

Exhaust steam enters the condensing 90 chamber 16 at 13, and is there met and condensed by sprayed cooling water which is delivered from water chamber 17 by passages 18, nozzle chambers 19 and nozzles 20. The commingled steam and water then pass 95 through the contracted portion of the partition 15 to hot well section A where the air and uncondensed vapors separate and pass upward to the air cooler for increase of pressure and reduction of volume previous to 100 withdrawal by the evacuating means.

The air and vapors enter the cooler by port 26 and pass around to the other side of the condenser through annular passage 25, being cooled during this movement by the 105 inner wall of the cooling element 21. Then

the air and vapors pass through port 27 to annular passage 23 in which they are cooled by the large outer surface of the cooling element 21 as they pass to connection 12 for withdrawal by the evacuating means.

The cooling water may be controlled by a valve in the inlet pipe as usual, but I prefer to use valves controlling the flow at or near the nozzles as by such a construction the excess head of water is utilized to secure increased pressure at the nozzles, thereby obtaining a finer division of the water and a more efficient condensation of the steam.

In the construction shown, two of the nozzles 20, preferably opposite ones, are controlled by valves, one of which will be described. The nozzle chamber 19 is provided with an opening in the condenser shell closed by a valve casing 1 which is provided with annular ports 2 registering with the passage 18. A tubular valve 3 sliding within the casing 1 controls the ports 2, and is connected by spider arms 4 and hub 5, to valve rod 6, which passes through stuffing box 7 and is connected to a suitably pivoted bell crank lever 8, actuated manually or otherwise by rod 9. The valve 3 is preferably of the balanced type, and so balanced that the pressure of the water will hold it in any position to which it has been moved. In the modification of this valve as shown in Fig. 4, the valve 3 is provided with an annular lip upon the inner end thereof against which the water acts as a positive means for holding the valve in its full open or closed position. In the intermediate position this lip has no effect as the pressures upon opposite sides thereof are balanced and the valve will thereby remain in any position to which it is moved.

A further feature of my invention consists in the provision of improved means for separating air from the condensing water previous to its delivery to the nozzles 20. This device is of the form shown, in which a chamber 28 is provided at one side of the water chamber 17 and separated therefrom by a wall 27' extending upward nearly to the water level in the chamber 17. A tube 29 connects the upper portion of the chamber 28 to the annular passage 23 in section B so that the air pump will remove such air as is collected in the upper portion of the chambers 28 and 17 by separation from the condensing water.

A valve 30 connected to float 31 by lever 32, pivotally mounted in bracket 33 secured to the chamber wall controls the inlet of the tube 29 to prevent the air pump from drawing water from the chamber 28 in case the water supply should become excessive. The float 31 may be guided by suitable means, as by pin 34 within plug 35. In order to direct the incoming water upward to cause a separation of the air in the upper portion of the

chambers 17 and 28, I provide a baffle 36 which crosses the chamber 17 at a short distance from the inlet connection 14.

By providing a separate chamber for the float and valve controlling the tube 29, I prevent the upward movement of the water from raising the float and closing the valve at times when this action is not necessary.

It will be understood that the invention is not to be limited to the construction shown and described, as many changes may be made therein while retaining the invention defined by the claims.

What I claim is:

1. A jet condenser having a condensing chamber, an air cooling chamber divided into annular passages for the passage of the air and uncondensed vapors through the cooling chamber, and a surface cooling element within the cooling chamber and between the passages.

2. A jet condenser having a downwardly contracted condensing chamber, and a water supply chamber having an annular projection forming an air cooler about the lower portion of the condensing chamber.

3. A jet condenser having a downwardly contracted condensing chamber, an air cooling chamber about the contracted portion of the condensing chamber divided into annular air passages and a water supply chamber having an annular projection between said passages.

4. A jet condenser having a condensing chamber, an air cooling chamber about the lower portion of the condensing chamber divided into annular air passages and a water supply chamber having an annular projection between said passages.

5. A jet condenser having a condensing chamber, a water supply chamber, an air cooling chamber, and a cooling element in the cooling chamber formed by a projection from the water supply chamber.

6. A jet condenser having a condensing chamber, a water supply chamber, an air cooling chamber, and a cooling element in the cooling chamber formed by an annular projection from the water supply chamber.

7. A jet condenser having a condensing chamber, a water supply chamber, an air cooling chamber, a cooling element in the cooling chamber formed by an annular downward projection from the water supply chamber, and means coacting with the cooling element to form annular passages for the passage of air and uncondensed vapors through the cooling chamber.

8. A jet condenser having a condensing chamber, a water supply chamber, an air cooling chamber, a discharge connection for the cooling chamber, a cooling element in the cooling chamber formed by an annular downward projection from the water supply chamber, means coacting with the cool-

- ing element to form annular passages for the passage of air and uncondensed vapors through the cooling chamber, a port connecting one of the annular passages with the 5 interior of the condenser on the same side thereof as the discharge connection, and a port connecting the two annular passages on the opposite side of the condenser.
9. A condenser having a hot well section 10 A, air cooling section B, and inlet section C, partition 15 forming downwardly contracting condensing chamber 16 and condensing water chamber 17, nozzles 20, passages connecting said nozzles and condensing water chamber, said condensing water chamber having annular projection 21 surrounding the lower portion of the condensing chamber 16, annular flanges 22, 24 forming with projection 21 and partition 15 passages 23 and 25, port 26 in flange 24 connecting passage 25 to the interior of the condenser, and port 27 in flange 22 connecting passages 23 and 25 whereby the air in its withdrawal passes first around one side of 15 projection 21 and then around the other.
10. A jet condenser having a condensing chamber, a plurality of nozzle chambers on said condensing chamber, nozzles secured in said nozzle chambers, a water sup-
- ply chamber, passages connecting the water 30 supply and nozzle chambers, and valve means controlling at least one of said passages.
11. A jet condenser having a condensing chamber, an air discharge connection, a 35 water supply chamber, means adapted to cause the separation of air from the water delivered to the water supply chamber, a connection for passing said air to the air discharge connection, and a float-control 40 valve controlling the inlet to said connection.
12. A jet condenser having a condensing chamber, an air discharge connection, a 45 water supply chamber, means adapted to cause the separation of air from the water delivered to the water supply chamber consisting of an air removal chamber separated from the supply chamber by a partition extending upward nearly to the water level in the supply chamber, a connection between 50 the upper portion of the air removal chamber and the air discharge connection, and a float controlled valve controlling the inlet to said connection.

In testimony whereof, I have hereunto set 55 my hand.

JOHN F. GRACE.
